UNITED STATES PATENT OFFICE.

ALEXANDER HAMILTON CLINE, JR., OF KANSAS CITY, MISSOURI, AND
JAMES HERRON DANVER, OF BEAVER, PENNSYLVANIA.

CONSTRUCTION OF LAVATORIES AND LIKE FIXTURES FOR DOMESTIC USE.

No. 842,527.

Specification of Letters Patent.

Patented Jan. 29, 1907.

Application filed March 10, 1906. Serial No. 305,397.

To all whom it may concern:

Be it known that we, ALEXANDER HAMILTON CLINE, Jr., and JAMES HERRON DANVER, residing at 2714 East Twenty-seventh street, 5 Kansas City, Missouri, and Beaver, Beaver county, Pennsylvania, respectively, citizens of the United States, have invented or discovered a certain new and useful Improvement 10 in the Construction of Lavatories and Like Fixtures for Domestic Use, of which improvement the following is a specification.

Our invention relates to improvements in the construction of lavatories and like fixtures for domestic use; and the object of our 15 improvement is a form of construction which is more sanitary and serviceable than others which are in use to-day.

The accompanying drawing is a view in side elevation, but with certain parts broken 20 away and shown in section, of a lavatory which is constructed according to our present invention.

This invention is particularly applicable to lavatories for domestic use, such as are commonly formed of porcelain or of enameled metal. It will, however, be understood that our invention is not limited in its scope by the material of which the lavatory is constructed.

The lavatory which is shown in the drawing consists, essentially, of a base portion or pedestal 1 and a bowl portion 2. As such lavatories are ordinarily constructed the bowl portion rests upon the top of the columnar base portion or pedestal—that is, at the point indicated by the letter A—and when so constructed the joint is for various reasons objectionable. It is a weak point in the structure. It is apt to become loose. It 35 is a point where corrosion is apt to occur and where dirt will lodge, giving an unsightly appearance and producing an unsanitary condition. Our improvement consists in prolonging or extending the upper end of the 40 base or pedestal portion 1 in a shell or apron portion 3, so shaped as to surround and support the bowl portion 2. As ordinarily constructed such a metal or porcelain lavatory is provided with a slab portion 4, formed integral with the bowl portion and extending 45 laterally from the edge of the bowl, and ordinarily this slab portion is finished at the edge

by an integrally-formed depending flange 5. We preferably secure the parts of our improved lavatory construction together by so 55 shaping them that the under surface of the slab extension of the bowl shall rest upon the upper edge of the apron extension 3 of the pedestal, and we preferably secure the parts at this point of contact. This may be done 60 by forming corresponding lugs upon the several portions of the structure and passing pins or bolts 6 through the adjacent lugs.

While our invention in its broader terms is not limited to the material of which the fixture is formed, there is a peculiar advantage 65 attributable to our invention when embodied in a fixture formed of enameled metal. Such articles are now ordinarily constructed of cast-iron with an enameled surface, and it will be 70 observed that in following the construction described above it is necessary to coat with enamel one side only of the metal castings, whereas in case the bowl portion as ordinarily 75 constructed rests directly upon the summit of a columnar pedestal portion it is necessary to coat with enamel both the inner and the outer surfaces of the bowl portion. The advantage of our improved construction 80 in this respect is obvious.

It will be understood that our improvement is applicable to lavatories and to structures of like general character, such as sinks and water-closets.

We claim as our invention—

In a lavatory or like fixture the combination of a bowl portion provided with a laterally-extending slab and with lugs formed upon the under surface of such extended slab, and a pedestal having an integrally-formed upward-extending shell surrounding said bowl portion and provided at the upper edge of such upward-extending shell with lugs engaging the lugs formed upon the edge of the bowl portion as aforesaid, substantially 95 as described.

In testimony whereof we have hereunto set our hands.

ALEXANDER HAMILTON CLINE, JR.
JAMES HERRON DANVER.
